UNITED STATES PATENT OFFICE.

WILLIAM J. FITZGERALD, OF BELOIT, WISCONSIN.

CONCRETE-WORKING MACHINE.

Application filed June 21, 1919, Serial No. 305,757. Renewed August 27, 1923.

To all whom it may concern:

Be it known that I, WILLIAM J. FITZGERALD, a citizen of the United States, residing at Beloit, in the county of Rock and 5 State of Wisconsin, have invented certain new and useful Improvements in a Concrete-Working Machine, of which the following is a specification.

My invention relates to devices for spreading concrete, more particularly in the construction of large buildings.

One of the objects of the invention is to provide an improved means for spreading the wet concrete and smoothing it in place 15 in pouring the floors of such buildings.

A special object is to provide a suitable support and set of tracks for a traveling spreader; said tracks to be mounted on the reinforcing rods used in the columns of the 20 building.

In the accompanying drawings, Fig. 1 is a section on the line 1—1 of Fig. 2 of a device embodying my invention, illustrating more particularly the mounting of the main 25 track on the projecting reinforcing rods. Fig. 2 is a plan view of my improved device and Fig. 3 is a section on the line 3—3 of Fig. 2.

In the embodiment of my invention selected for illustration, a pair of main tracks 30 A extending for a considerable distance and preferably for the entire length of the building to be constructed, carry a traveling frame B. A smaller frame C is mounted 35 on tracks on the frame B extending transversely to the tracks A and carries a pivotally mounted tool or trowel D for spreading the concrete.

In the erection of a large building of 40 reinforced concrete, the reinforcing metal rods in the columns are customarily allowed to project a considerable distance above the level of any given floor. After the floor in question has been finished, these rods are 45 imbedded in the concrete of the columns supporting the next floor above and form a tie between two floors. At the time a given floor is being poured, these upwardly projecting rods are the only solid foundation 50 available for mounting tracks, scaffolding or any sort of machinery. I have provided means for mounting the tracks A on the projecting ends of these reinforcing rods comprising plates 9 associated with any desired number of angles 10 suitably bolted to

them. Each angle 10 extends vertically downward and at its lower end carries a U-bolt 11 adapted to embrace and clamp one of the reinforcing rods 12. In mounting the plates on the reinforcing rods, enough 60 angles are used to provide a firm support. The rods 12 need not all touch the plate 9 or even be cut off at or below the level of the plate as one or two rods projecting above the level can be easily bent to one side out 65 of the way. I-beams 13 bolted end to end by suitable clips 14 bridge the space between adjacent plates and support the main rails A.

Where the span between adjacent columns 70 is very great, a considerably lighter beam for supporting the main rails A may be used if temporary vertical braces or struts are used to brace each span to the wood false flooring on which the concrete is poured. The sidewise rigidity necessary to insure 75 against buckling may also be diminished with a resultant saving in the size of beam required by intermediate struts or braces running out to the side and diagonally down 80 to the floor level. All such braces may, of course, be removed as soon as the carriage has completed the work and passed on to the next section of track. In fact, the track, 85 itself, is removed for use in a new position.

The main carriage B comprises a pair of end channels 15 and a pair of transverse I-beams 16 supporting the rails 17 and forming with said channels a rectangular frame. Axles 18 suitably journaled in 90 bearings 19 fastened to the webs of the channels 15 and reinforced by any convenient number of intermediate bearings 20 carry wheels 21 engaging the main rails A to support the main carriage B. The small 95 carriage C comprises a similar rectangular frame work formed of channels 22 and 23, the latter having suitable bearings 24 to receive the ends of the axles 25 carrying wheels 26 upon which the carriage C rolls. The vertical rod 27 carries the trowel D 100 suitably secured to the lower end of said rod and extends upwardly through a tube 28 suitably fastened to plate 29 on the carriage C, through a bushing 30 on the upper plate 105 31, and at a suitable distance above the carriage carries a hand wheel 32. Collars 33 and 34 restrain the shaft from endwise movement.

Means are provided for moving the main 110

carriage B along the main rails A and also for moving the small carriage C along the transverse tracks 17. Herein I have shown two hand wheels 35 and 36 adapted to be 5 operated by a workman standing by them. The hand wheel 35 is illustrated as connected to one of the axles 18 by being mounted directly on a suitable prolongation of said axle. Any other suitable transmission 10 for this purpose may of course be employed. The hand wheel 36 rotates the shaft 37 carrying the drum 38 suitably mounted on brackets 39 extending from the channel 15. A cable 40 is attached at 41 to one side of 15 the carriage C and passes several times around the drum 38 thence back to the other end of the carriage B over a suitable idler pulley 42 to be attached at 43 to the opposite side of the carriage C. It will be seen 20 that the workman stationed by the two wheels 35 and 36 can move the carriage C in any direction by suitable manipulation of the wheels.

Another workman stands upon and is carried to and fro by the carriage C and operates the trowel D by means of the hand wheel 32. While the trowel D may be of any desired form and might for instance extend in opposite directions from the shaft 25 27, I prefer the form illustrated as less clumsy to handle and more efficient in working close up to the reinforcing rods 13 than a double ended trowel. It will be seen that I have provided a suitable system of tracks 30 for the operation of a trowel or tool over large areas of concrete without the necessity of a workman walking on the concrete being poured. It is within the scope of my invention to operate one or all of the hand 35 wheels 32, 35 and 36 by a suitable source of power such as a gasoline engine or an electric motor thereby dispensing with one of the operators.

While I have shown and described in detail 40 the embodiment of my invention at present preferred, it is obvious that many improvements and modifications will naturally occur to those skilled in the art. I aim in the subjoined claims to cover all such legitimate 45 modifications and improvements.

I claim as my invention:—

1. In concrete working machinery, in combination, a pair of tracks mounted above the floor level of a building, a carriage 50 mounted on said tracks and slidable along the same, means for sliding the carriage, and a concrete spreading and smoothing tool horizontally mounted on the carriage, and means for rotating said tool in a horizontal plane.

2. In concrete working machinery, in combination, a pair of tracks, a traveling carriage on said tracks, a second pair of tracks on said carriage extending transversely to the first mentioned pair of

tracks, a second carriage slidable along the second pair of tracks, means for sliding the first mentioned carriage, means for sliding the second mentioned carriage, said means for both carriages being simultaneously or separately operable from the same side of said machine a concrete spreading and smoothing tool mounted on the second carriage so as to be vertically adjustable, and means for freely rotating said tool in a horizontal plane. 70

3. In concrete working machinery, in combination, a pair of tracks, a traveling carriage on said tracks, transverse tracks on said traveling carriage, a second carriage slidable on said transverse tracks, a concrete spreading and smoothing tool horizontally mounted on said second carriage, means for vertically adjusting said tool, means for freely rotating said tool in a horizontal plane, and means for sliding said second mentioned carriage along said transverse track comprising, a drum at one end of said first mentioned carriage, an idler-pulley at the other end of the said first mentioned carriage, a rope having its ends attached to opposite sides of said second mentioned carriage and passing around said idler-pulley and drum, and means for rotating said drum. 80

4. A concrete finishing machine having, in combination, a concrete spreading and smoothing tool mounted for rotation about a vertical axis, manual means for controlling the rotation of said tool, and means for moving said tool across the surface to be finished in contact with the concrete to spread and smooth it. 95

5. In concrete working machinery, in combination, means for mounting a track on the reinforcing rods projecting above the unfinished upper ends of the columns of a building, comprising a plurality of angles each having a vertical leg clamped to one of the reinforcing rods, and a horizontal leg, and a plate laid across the horizontal legs of a plurality of angles and supported thereby. 105

6. In concrete working machinery, in combination with a plurality of vertical supporting members, a plurality of supports each comprising a horizontal plate, a plurality of angles attached to each horizontal plate and having downwardly projecting legs, and means on each downwardly projecting leg for clamping engagement with a vertical supporting member. 110

7. In machinery for laying concrete floors, a pair of tracks extending from end to end of a building, and spaced apart laterally by the distance between adjacent rows of vertical columns of said building, a traveling carriage on said tracks, a second carriage transversely movable on said traveling carriage over substantially the entire distance 120 125 130

between said first mentioned tracks, and means at one side of said first mentioned tracks for sliding both of said carriages.

8. In concrete working machinery, in combination with a plurality of groups of irregular upwardly projecting members, a support associated with each group and carried thereby and means carried by said support for mounting it in place on said members, said mounting means being adjustable to allow for the irregularity of said members.

9. In concrete working machinery, in combination with a plurality of regularly spaced groups of irregular upwardly projecting members, a support associated with each group, adjustable means engaging the members of each group for mounting the support on the group, and tracks laid on the supports.

10. In testimony whereof, I have hereunto set my hand.

WILLIAM J. FITZGERALD.
